45 Claims.

(Cl. 82—14)

This invention relates to machines in which operative mechanism is controlled by a pattern relative to which a tracer is traversed. Such a machine, for example, may be a lathe, milling machine, shaper, grinder, die sinker, or the like, whereby work is to be shaped by a suitable tool in accordance with a pattern. One of the problems arising in connection with such pattern control consists in causing the tracer to accurately follow a pattern having abrupt shoulders in such a way that the tool will describe correspondingly abrupt shoulders relative to the work. Such a control or follow-up system comprises in general the pattern, a tracer which is moved along the pattern, a moving system carrying the tracer, a tool, the work, and mechanism for moving the tool and work relatively responsive to small variations in the line of feed between the tracer and its supporting means and which at the same time tends to reduce these variations.

One of the objects of this invention is to provide a tracer mechanism so constructed that on engagement of the tracer with an abrupt shoulder on the pattern, it is given an immediate and rapid withdrawal to the extent necessary to clear the shoulder and to counteract frictional drag between it and the pattern in so doing.

A further object is to provide a tracer which will immediately follow a sudden steep depression in the pattern and cause the tool to make a correspondingly steep cut in the work.

A further object is to provide a tracer mechanism which does not require a continuous pattern for its control, thus to facilitate variations of pattern.

A still further object is to provide various types of tool-controlling mechanism responsive to the tracer mechanism.

For a more complete understanding of this invention, reference may be had to the accompanying drawings in which

Figure 1 is a fragmentary top plan of a lathe provided with the pattern-controlled mechanism.

Figure 2 is a section on line 2—2 of Figure 1.

Figure 3 is a top plan, a portion of the tracer casing being broken away, of the pattern and the tracer mechanism.

Figure 4 is a section on line 4—4 of Figure 3.

Figure 5 is a section on line 5—5 of Figure 4.

Figures 6, 7 and 8 are detail perspectives of certain portions of the tracer mechanism.

Figures 9 to 12 inclusive are diagrammatic views illustrating the action of the tracer mechanism as the tracer encounters various pattern con-

figurations and illustrating the corresponding responses of the tool mechanism.

Figures 12a and 12b together constitute a wiring diagram for control of a machine such as is illustrated in Figures 1 and 2.

Figure 13 is a diagrammatic view illustrating contours of tracer point and tool for the tool to operate in accordance with the pattern, the idle side motions of the tracer being much exaggerated.

Figures 14 to 16 are diagrammatic views illustrating certain tracer positions corresponding to certain angular pressures exerted thereon as by contact with a pattern.

Figure 17 is a front elevation partly broken away showing a lathe having a pattern-controlled hydraulically-actuated tool.

Figure 18 is a detail section on line 18—18 of Figure 17.

Figure 19 is a fragmentary top plan of the same.

Figures 20 to 23 inclusive are diagrammatic views illustrating the response of the hydraulic mechanisms to various pattern-controlled tracer positions.

Figure 24 is a fragmentary plan of a tracer mechanism provided with electrical controlling devices.

Figures 25 and 26 are detail sections on the correspondingly numbered section lines of Figure 24.

Figures 27 to 30 inclusive are diagrammatic views illustrating the response of the electrical tool-controlled mechanism using the tracer of Figures 24 to 26 inclusive for various pattern-controlled tracer positions.

Figure 31 is a transverse section through a lathe having pattern-controlled mechanical actuation of the cutting tool.

Figure 32 is a detailed section on line 32—32 of Figure 31.

Figure 33 is a view similar to a portion of Figure 31 but to a larger scale.

Figure 34 is a detail section on line 34—34 of Figure 33.

Figure 35 is a top plan of a discontinuous pattern and a tracer mechanism formed to cooperate therewith.

Figure 36 is a fragmentary side elevation of the same.

Figure 37 is a detail section on line 37—37 of Figure 35.

Figure 38 is a fragmentary plan similar to a portion of Figure 35, but showing the tracer mechanism in a different position relative to the pattern.

Figure 39 is a detail section on line 39—39 of Figure 35.

Figure 40 is a detail section on line 40—40 of Figure 38.

- 5 By way of example this invention has been illustrated as applied to a lathe, though it should be understood that it is applicable to a great variety of machines in which the control of a tool with relation to work is to be produced 10 through the action of a tracer with reference to a pattern and whether or not the tool is a cutting tool.

As shown in Figures 1 and 2 the lathe is provided with a conventional form of bed 1 on which 15 is mounted for longitudinal sliding a traversing carriage 2. This carriage has mounted thereon for motion transverse to its own motion a feed carriage 3. While various means might be provided for moving these carriages, an electric motor F is shown for actuating the feed carriage to produce feed and retraction between the tool and the work and a similar motor (not shown in these figures) may be used to effect the traverse motion as through a suitable lead screw 4. On the 20 feed carriage 3 is shown mounted a tool holder 5 carrying a tool 6.

The work W to be operated upon by the tool is carried by any suitable work support, herein shown as comprising centers carried by the lathe 30 headstock 10 and the tailstock 11, the headstock having a suitable driving connection to the work, as for example, the lathe dog 12. At 15 are shown supporting brackets for a table 16 on which a pattern 17 may be fixed in any suitable 35 manner. As shown the table 16 is provided with a series of electromagnet poles 18 which when energized retain the pattern 17 securely thereon, the pattern being thus readily adjustable with respect to the table. This pattern may be of steel 40 or other magnetic material so that it may be held firmly by the magnet poles 18. Any other suitable means for holding the pattern might, however, be substituted and the pattern may be made of any suitable material.

45 The feed carriage 3 also supports a tracer mechanism indicated generally at 20 having a tracer 21 mounted to be traversed by the longitudinal motion of the carriage 2 along the edge contour 22 of the pattern. During this traverse 50 the tracer element 21 may be caused by means hereinafter described to move in and out to follow the pattern contour, small variations from a null relative position between the tracer element 21 and the remainder of its mechanism acting to 55 control the feed and retractive motions of the feed slide 3 in corrective directions, the motion of this slide both in feed or retraction and in traverse being simultaneous with the movements 60 of the tracer mechanism 20, so that the tool 6 may form on the work a contour similar to the pattern contour.

65 The tracer mechanism construction by which the tool motions may be controlled will now be explained. Referring to Figures 2 to 8, it will be noted that the mechanism 20, which is shown as enclosed within a casing 30, comprises a support 31 which is fixed relative to the base 32 of the casing and so is mounted rigidly with the feed carriage 3. For convenience in supporting 70 certain of the control parts, this support 31 is shown as provided with a cylindrical post 33. This support carries for yielding motion in one direction in a plane a member 34, which as shown best in Figure 7, may be a plate of rectangular 75 outline with a central opening 35 through which

the post 33 extends loosely. For supporting this member 34 for yielding movement in a single rectilinear direction four leaf springs 36 are shown, these springs being arranged in pairs on opposite sides of the member 34 engaging in suitable notched recesses 37 in the support 31 and in similar notched recesses 38 in the member 34. Since these leaf springs 36 are of substantial width they prevent relative motion of the member 34 to the base 31, except in a rectilinear direction indicated by the arrow x in Figure 7. This member 34 movably supports a similar member 40, shown detached in Figure 6, to which is fixed the tracer 21 which extends out through an opening in the casing 30 and impinges on the pattern. This member 40 is supported from the member 34 for motion in a line at an angle to the line of motion of the member 34, as indicated by the arrow y in Figure 6. For this purpose leaf springs 41 are shown as secured in suitable recesses 42 in each of opposite sides of the member 40 and are also secured similarly as in recesses 43 in the member 34. Thus the tracer 21 is movable relative to the member 33 only in the rectilinear direction of the arrow y, 25 and the member 34 is movable with respect to the base 31 only in the rectilinear direction of the arrow x. By compounding these motions, however, the tracer 21 is permitted a movement in all directions in a single plane with reference to the 30 base 31. The tracer mechanism is so mounted on the feed carriage 3, however, that the line of feed and retraction is between the directions indicated by the arrows x and y, so that in order for the tracer 21 to move in the line of feed, 35 the member 40 must move relative to the member 34 in line with the arrow y and the member 34 must move with reference to the base 31 in line with the arrow x. While as shown both the members 34 and 40 are of rectangular outline 40 so that the directions of the arrows x and y are at right angles to each other, this particular relationship is not necessary, it being possible to vary these angles with relation to each other as 45 will later be more fully set forth.

In order that the tracer may tend to follow depressions or valleys in the pattern contour, it is pressed against the edge of the pattern by the leaf springs 36 and 41 and is rearward in the feed and retractive direction from its normal 50 position of rest with the leaf springs 36 and 41 in balanced condition when the tracer is in what may be termed a null position in which it exerts no effect to actuate the feed slide in either direction. It is in this condition, as shown in Figure 3, when the pattern-engaging point 45 of the tracer is being moved along a contour such as c—d of the pattern which is parallel to the traverse direction of the carriage 2. Should the tracer point come to a depression in the pattern, as, for example, after leaving the pattern contour at b as shown in Figure 9, the springs 36 and 41 immediately move the tracer inwardly from its null position and thereby act to operate 65 the feed mechanism to feed the tool and the tracer as will later more fully appear. This forward motion of the tracer with reference to the support 31 is limited by two stops, these as shown being the screws 50 and 51. The screw 50 is 70 carried by an upstanding arm 52 secured to the support 31 between the springs 36 on that side of the support nearest to the pattern and acts to limit the motion of the member 34 in the direction of the arrow x inclined toward the pat- 75

tern. The stop screw 51 is carried by a similar arm 53 secured to the member 34 between the springs 41 which extend between the members 34 and 40, and thus acts to limit the movement 5 of the tracer 40 by flexure of the springs 41 with reference to the member 34 in a direction also inclined toward the pattern.

This arrangement of the spring supports and stops insures that any force applied to the tracer 10 point 45 by its engagement with the pattern throughout somewhat more than an angle of 90° from retracting direction acts to move the tracer back from its null position so as to cause retraction of the tool from the work. This is illustrated 15 in Figures 14, 15 and 16. The line of feed and retraction is lengthwise of the tracer axis. A force exerted directly back on the tracer point, of course, will act to flex both sets of springs 36 and 41, the member 40 moving in line with the arrow *y* backwardly and inclined to the left as viewed in Figure 16, and the springs 36 flexing and allowing the member 34 to move backwardly 20 in the direction of the arrow *x* and inclined to the right. If, however, the pressure angle is 45° removed with respect to longitudinal axis of the 25 tracer arm 21, as shown in Figure 15, the springs 41 cannot act, since the force is widthwise thereof, so that the motion of the tracer is backward and to the right, due to the flexing of the springs 36 only. This, however, results in a component 30 of motion of the tracer rearwardly from its null position to cause retraction of the feed carriage as will later appear. If now the force exerted on the tracer point is more than 45° to the axis of the arm 21 in any of the directions shown by the 35 arrows *u*, *v* and *w* in Figure 14, member 40 is moved relative to the member 34 in the direction of the arrow *y* inclined toward the pattern until further motion is stopped by the impingement of 40 the member 40 against the stop screw 51. At the same time the force on the tracer acts to move the member 34, flexing the springs 36 in a direction away from the stop screw 50, so that the resultant motion of the tracer is a motion to the 45 right and then diagonally rearwardly as shown by the arrow *z* in Figure 14. The force in the directions of any of these arrows *u*, *v*, and *w* may be resolved into two forces at right angles to each other (see the small diagrams at the right of the 50 tracer point in Figure 14), one being in the line of the arrow *x* and in the direction to retract the tracer. The other being in the direction of the arrow *y* is ineffective after the stop 51 has been contacted. Thus a force is exerted on the tracer 55 point more than 90° removed from the retraction direction of the tracer as shown by the arrow *w* acts to retract rather than to advance the tracer. Of course should the direction of traverse be in the reverse direction to that shown, a force 60 exerted throughout an angle of more than 90° on the other side of the line of feed and retraction would similarly act to produce a component of motion of the tracer rearwardly. While, as will later appear, there is no means for temporarily 65 reversing the direction of traverse to cause the tracer to follow an undercut shoulder, a rectangular shoulder being all that it is called upon to encounter and follow, nevertheless the angle between the arrows *v* and *w* which has a component 70 which would apparently move the tracer point in feed rather than retraction direction, but which actually causes the retraction of the tracer, as previously described, produces a component of retraction force which tends to overcome any frictional drag between the tracer point and the pat- 75

tern which might tend to actually prevent retraction of the tracer should the angle of force causing such retraction be limited to 90° from the line of feed and retraction.

As hereinbefore pointed out, it is not essential 5 that the directions of the movements between the member 34 relative to the base 31 and the member 40 relative to the member 34 be at right angles to each other. Where the angle with reference to the feed direction is more obtuse than 10 this the amount of side motion of the tracer relative to its axial movement is increased as is also the angle through which a force exerted on the tracer point is effective to cause its retraction rather than its forward feed. A more acute angle 15 between these directions will produce the reverse effects.

In Figures 9 to 12 are shown diagrammatically the movements of the tracer point with respect to its null position when it encounters various 20 contours on the pattern. For the purposes of such illustration the control of the feed and retractive motions of the tool and the tracer mechanism as a whole are shown diagrammatically as of the type more fully described and claimed in the application for patent of Albert Allen, Serial No. 609,139, filed May 4, 1932, for Automatically controlled machine tool and follow-up system for which this tracer mechanism has been more particularly designed. It should, however, be understood that it is not limited to any particular type 30 of tool control, various other controls being shown in detail in this application. The control shown diagrammatically in Figures 9 to 12, however, includes an electrical condenser plate 60 secured 35 to a suitable fixed portion of the tracer mechanism which partakes of the motion of the tool carrier only, as, for example, the cylindrical post 33, to which the plate 60 may be secured as by an angle bracket 61 as shown in Figure 5. The tracer 40 member 40 which partakes of all the movements of the tracer element 21 is shown as carrying a condenser plate 63. These condenser plates remain parallel throughout the relative motions between the member 40 and the post 33 and in 45 the null relative position of the tracer these plates define an electrical capacity of an amount which causes no motion of the feed motor F. The traverse motor T may then operate to effect relative traverse between the tracer and the pattern and 50 between the tool and the work without any feed whatever. This will cause the tool, if in operative relation to the work, to produce a cylindrical outline thereon and is the condition produced when the tracer is traversing any portion of the pattern 55 parallel to the line of traverse.

Supposing now, as in Figure 9, the tracer point reaches the shoulder *b* so that it becomes unsupported by the edge of the pattern at an abrupt shoulder, the springs 36 and 41 then 60 immediately throw the tracer forwardly into the position shown in Figure 9, bringing the condenser plate 63 closer to the condenser plate 60 and increasing the capacity of these plates from their null value. This immediately acts through 65 the mechanism in the control box 65 to energize the feed motor to feed the tool into the work and the tracer toward the pattern, and at the same time stops the longitudinal traverse motor T because of the sudden and marked increase of 70 capacity between the plates 60 and 63. Thus the tool feeds in straight and produces an abrupt shoulder on the work. This takes place until the tracer, being stopped by the pattern at *c* 75 while the feed continues slightly thereafter.

presses back, separating the condenser plates 60 and 63 to their null relation, stopping the feed motor and causing the traverse motor to resume full speed.

- 5 If the tracer point strikes an abrupt shoulder as at *d* in Figure 10, it is moved laterally and backward, as previously explained, suddenly separating the condenser plates from their null relation, which acts to stop the traverse motor and 10 to actuate the feed motor in the reverse direction to withdraw both the tool and the tracer from the pattern and work respectively. As soon as the traverse motor has withdrawn the tool and the tracer sufficiently for the condenser plates to 15 return to their null relation, the feed motor is stopped and the traverse motor again takes up its load as previously. Such a condition is illustrated in Figure 11 where the tracer has just passed the shoulder *f*.
- 20 Where the tracer is moving up or down an inclined path both the work feed motor and the traverse motor are actuated. The tracer going down the incline is shown in Figure 12, in which the condenser plates 60 and 63 are closer than at 25 their null position, but never sufficiently far from their null relation to actually stop the traverse motor T.

In Figures 12a and 12b is shown a diagram of one arrangement by which the traverse and feed control may be actuated by the variable capacity due to variable spacing of the condenser plates 60 and 63 of Figures 9 to 12 in accordance with the Allen application hereinbefore mentioned. The leads 450, 451, 452, 453 are common to these 30 two Figures 12a and 12b. Capacity variations due to variable spacing of the condenser plates 60 and 63 change the tuning of a secondary circuit including the condenser plates 60 and 63 and an inductance 500, relative to resonance with an exciting oscillatory vacuum tube circuit indicated as a whole at 501 in Figure 12a and thus vary the 35 voltage induced in this secondary circuit. As shown this voltage is amplified by the radio frequency vacuum tube amplifier unit at 502 and it is then rectified and filtered by rectifying and 40 filtering units 503 and 504 to produce a substantially direct current flow through the resistors 505 and 506 and consequently to produce a substantially smooth direct current potential across 45 each of these resistors which varies in amount in accordance with changes in capacity due to space 50 changes between the condenser plates 60 and 63. These direct current voltages together with proper amounts of direct current voltage from a drop 55 resistor 507 of a power supply unit 508 and alternating current voltage of the proper phase and magnitude from the unit 509 are used to control the grid circuits of power gas filled tubes 511 and 512 which control the direction and rate of motion of the feed motor F. Such a power tube 60 passes cathode-plate current whenever the grid is biased sufficiently positive and when once opened continues to pass such current as long as this current remains in the same direction 65 regardless of subsequent grid bias. By the combination of the alternating and direct voltage bias herein employed the time in each positive half cycle at which cathode-plate current starts to pass is controlled, this current passing for the remainder of this half cycle so that the power 70 passed to the variable speed feed motor and consequently the speed of this motor is dependent on this voltage bias. The connections from the resistors 505 and 506 are reversed to the power tubes 511 and 512 (see Figure 12b) so that the 75

positive grid bias of one of these tubes, shown as the tube 511, rises by increase of capacity of the condenser comprising the plates 60 and 63, and the positive grid bias of the other tube 512 falls. The circuit constants are so adjusted that in null 5 condition of the condenser plate neither tube passes current to actuate the motor F, but if the capacity is less than null the tube 512 passes current and the feed motor F operates in a direction to increase this capacity, moving the tracer to 10 ward the pattern until it is stopped and the capacity is brought back to null, and if the capacity is more than null the tube 511 passes current and the feed motor F operates in the reverse direction. These tubes feed to the reverse direction motor field windings 513 and 514, respectively, of the feed motor.

The control of each of these tubes 511 and 512 is also modified by the direct current voltage across the armature of the feed motor to act 20 as a corrective follow up to prevent excessive over-travel of this motor in either direction.

The control of the traverse motor T is effected by the power tube 515, the grid of which is biased by suitably phased alternating current voltage 25 from the unit 509, direct current voltage from the resistor 501, and direct current voltage derived from the voltage across the armature of the feed motor F smoothed out by a suitable choke and condenser. This latter voltage is 30 made the controlling variable, the other biasing voltages being so arranged and adjusted that with the feed motor running at full speed in either direction the traverse motor is stopped and with the feed motor stopped the traverse 35 motor is running at full speed, and with uniform complementary speed variations of these motors in between stopped and full speed. This complementary speed variation provides for all slopes of taper of the tool operating on the work from 40 zero to 90°. Power for the feed and traverse motors, which are direct current variable speed motors, is derived from the transformer 516.

That portion of the diagram of Figure 12b to the right of the dotted lines 520 to 524 inclusive 45 relates to manual and automatic control for returning the traversing carriage to its starting position after the completion of a traverse and while the tracer and the tool are held retracted from the pattern and work, respectively, and is 50 not directly involved in the present invention. All this is fully described in the Allen application to which reference has hereinbefore been made, in which also the capacity variation motor control has been explained in greater detail than 55 herein.

Other means for accomplishing this control, not dependent on capacity changes of a condenser, will be later explained in which the same relationship of co-ordinate control of the feed 60 and traverse motors is employed. The condenser mechanism, however, affords a control mechanism continuously variable with variations of the tracer from null position and makes possible continuous motor control of great accuracy so 65 that accurate pattern control is possible.

From the foregoing description it will be noted that the tracer point is movable relative to the tool both in the line of feed and in the line of traverse and that the lateral motion in the line of 70 traverse is ineffective, that in the line of feed being the one which is relied upon to produce the corrective control of the tool to follow the pattern. In Figure 13 is shown diagrammatically the manner in which this relative lateral motion 75

may be corrected for in the accuracy of motion of the tool in following the contour of the work and how it corrects for variation from null of the tracer. This is done by forming the work-engaging portion of the tool and the pattern-engaging portion of the tracer of the same contours except that the tracer point is made of a width greater than that of the tool by the amount of this relative side motion. Thus in Figure 13 the 5 tracer point contours are shown in dotted lines with the corresponding positions of the tool in solid lines, following a curve which takes in all angular pressures to which the tracer is subjected by its engagement with the pattern contour. Thus, assuming a travel in the direction of the arrow shown in this figure, as the tracer passes downwardly into a contour valley as at 70, it is forwardly of the position of the tool by the amount of side slip and is slightly inwardly of it by reason of its being positioned forwardly of the null position in order to give a control motion of the tool in a direction to feed into the work. This takes place until the tool and the work reach their lowest positions, whereupon the tracer 10 point is returned to its null relation and the tool point is in exact alignment therewith in the direction of traverse as at 71. The tracer is then drawn slightly backwardly with relation to the tool by its frictional engagement with the pattern. As the tracer engages a portion of the pattern of less depth the tracer is then moved back of its null position, which actuates the feed mechanism in the reverse direction to withdraw the tool, whereupon the tool is projected slightly inwardly of its corresponding tracer position and the tracer engages the pattern slightly forwardly of the corresponding tool engagement of the work. The tracer then falls progressively behind in the line of traverse until the forward edge of the tool 15 and the forward edge of the tracer are in alignment while the tracer is so far back from the tool contour that the traverse motion of the tool is stopped and it is being retracted only, as shown at 72. The pattern thereafter presenting a portion permitting traverse of the tracer, it begins to move ahead of the tool in the direction of traverse and the tool starts to catch up with it in the retracting direction, the amount of variation of the tracer from its null position becoming less and causing an increasing traverse motion of the tool. This increase in traverse and decrease in retraction takes place until the point 20 73 is reached, where there is no feed or retracting motion of the tool or the tracer and the motion is entirely a traversing motion. As an inwardly inclined portion is reached, the tracer then runs ahead in line of feed due to its lateral motion and also runs further inward along the pattern, whereupon a feed motion of the tool and tracer inwardly is produced and the traverse motion is slowed, until at the point 74 the tracer is ahead in the line of traverse as in the position shown at 70 and it is so far from its null position inwardly 25 that the tool is given a feed motion only. From this diagram it will be seen that by so proportioning the tool and the tracer point extreme accuracy of follow-up of the tool through the control by the tracer may be produced, the lateral motion between the tracer and the tool acting to correct for the small variations in position in the line of feed between the tracer and the tool, by which variations the feed and retractive motions, and correlative thereto the traverse motions, are 30 controlled. In this diagram the amounts of such

motions have been much exaggerated in order to better show the principle of operation.

In Figures 17 to 23 inclusive a fluid pressure, preferably hydraulic, actuation of the traverse and feed and retractive motions controlled by the tracer mechanism is illustrated. The traversing motion is produced by means of the hydraulic cylinder 100 within which is movable a piston 101 connected as through a piston rod 102 with the traversing carriage 2a, while the feed and retractive motions are produced by a hydraulic cylinder 103 carried by the carriage 2a and connected to the feed carriage 3a by the piston 104 and the piston rod 105. A suitable source of liquid under pressure is employed, as, for example, the pump shown conventionally at 106 in Figure 19, from which pressure and discharge lines 107 and 108, respectively, lead to a valve casing 109 shown in detail in Figures 20 to 23. This casing 109 has a piston valve 110 therein which is connected as through a lever mechanism 1110 with the tracer member 40 so that the position of the valve 110 in the valve casing is determined by the position of the tracer in so far as its motion in the line of feed is concerned. 25

The size of the valve is much exaggerated in Figures 20 to 22 with relation to the sizes of the traverse and feed cylinders 100 and 103, respectively, in order that its operation may be more clearly understood. With the connections shown 30 the traverse is from right to left. In Figure 20 the tracer is shown in its null position as when traversing a portion of the pattern parallel with the line of traverse. In this position a portion 111 of the valve 110 closes communication from 35 both pressure and discharge sides of the valve to the outer end of the feed cylinder 103, and valve portions 112 and 113 likewise close off the inner end of the feed cylinder 103 from both pressure and exhaust sides. The pressure pipe 40 107, however, communicates through the valve groove 114 with the pipe 115 leading to the right hand end of the traversing cylinder 100 so that the tool carriage, together with the tracer mechanism, is being traversed relatively to the work 45 and to the pattern.

In Figure 21 the tracer is shown as being traversed along an outwardly tapering face of the pattern so that it is pushed in reTRACTING direction from its null position, thus displacing the 50 valve 110 so that the outer end of the feed cylinder 103 is in communication with the discharge pipe 108 and the inner end of this cylinder 103 is in communication with the pressure pipe 107 through the groove 116 and pipe 118. The feed 55 cylinder is thus operating to withdraw the tool from the work. At the same time the pressure pipe remains in communication with the right hand end of the feed cylinder 100 through the pipe 115. Thus there is both traverse and withdrawal of the tool so that a taper cut results. By graduating the sizes of the port openings the proper ratios of traverse and retraction may be produced to accurately follow the taper of the pattern. Should these proportions not be exactly 60 correct, the valve would alternately over and under correct and the taper would be cut by a series of slightly stepped formations rather than by a uniform taper.

If now the tracer impinges on a shoulder on 65 the pattern, the valve 110 is driven further outwardly from the null position, as shown in Figure 23, in which position the supply of fluid pressure to the traverse cylinder 100 is cut off by the portion 112 of the valve so that the traverse of the 70 75

tool stops, but the withdrawal motion proceeds so that the tool cuts a correspondingly abrupt shoulder on the work. If now the tracer reaches a sharp inwardly extension of the pattern configuration as shown in Figure 22, it immediately feeds forward rapidly causing the valve 110 to assume the position shown in Figure 22 in which the supply of fluid under pressure to the traverse cylinder 100 is cut off by the valve portion 113 and pressure is supplied through the pipe 117 to the outer end of the feed cylinder 103 while the inner end of this cylinder is open to the discharge through the pipe 118 beyond the end of the valve 113 adjacent to its portion 113. The feed carriage 15 is then fed inwardly to form a sharp shoulder similar to that on the pattern, the feed cylinder only being in operation. When the base of this depression is reached by the tracer, a slight forward movement of the feed beyond this brings 20 the tracer back to its null relation, whereupon the conditions shown in Figure 20 are resumed with the traverse cylinder in operation and the feed cylinder inoperative.

In Figures 24 to 29 a simplified electrical control mechanism is illustrated. Carried by a portion of the tracer mechanism, as, for example, the post 33, are four spring contacts 200, 201, 202 and 203 riding in tubes 206. Rigid with the tracer, as by being mounted on the tracer member 40, are a pair of contact posts 204 and 205 which may impinge the spring contact pins 201 and 202 and similar abutment contacts 207 and 208 may impinge on the contact pins 200 and 203, respectively. The pin 201 is longer than the pin 202 and pin 200 is longer than the pin 203, so that on backward motion of the tracer in the direction of retraction of the tool carriage, contact is first made between the contacts 204 and 201 and then on further motion contact is also made between the contacts 205 and 202, while on motion of the tracer in the feed direction connection is first made between the contacts 207 and 208 and then between the contacts 208 and 203. These contacts are connected to control 45 the feed motors F and traverse motors T, preferably through suitable relays in the control box 210. In the null position of the tracer the contacts at 207 and 200 and 204 and 201 are closed together, respectively, thus completing the circuit through the traverse motor to produce relative traverse between the tool and the work and between the tracer and the pattern, respectively, thus producing a straight cut on the work 50 conforming to a portion of the pattern parallel to the line of traverse. If now the tracer is moved outwardly, as by engaging with an outwardly tapered face of the pattern, as shown in Figure 28, the tracer is moved backwardly from its null position, thus bringing the contact 205 into engagement with the contact 202, energizing the feed motor F in a direction to withdraw the tool and the tracer mechanism from the work and the pattern, respectively, but so long as the tracer is not too far from its null position, the contacts at 200 and 207 and 201 and 204 are still in engagement so that the traverse motor is still being operated. This results in a taper cut on the work. If now the tracer impinges on a shoulder on the work as in Figure 29, the tracer is suddenly moved backwardly to an extent further than that shown in Figure 28, breaking the connection between the contacts 200 and 201, so that the traverse motor ceases to be energized while the feed motor continues in a direction to withdraw the tool from the work and

the tracer from the pattern. Since there is no longer any traverse motion, the tool is brought directly outwardly by this retractive motion of the feed motor, thus forming an abrupt shoulder on the work corresponding to that on the pattern. If now the tracer falls off an abrupt shoulder on the pattern, the tracer moves forwardly so far from its null position that both the contacts 204 and 205 are withdrawn from connection with their mating contacts 201 and 202, while the contact 208 is brought into operative engagement with the contact 203. This energizes the feed motor to feed the tool and the tracer into the work and pattern, respectively, while the traverse motor is disconnected. In case an inward 15 taper is engaged by the tracer the tracer does not move inwardly sufficiently to separate the contacts 201 and 204 so that the traverse motor as well as the feed motor is energized. Thus the tool is given a motion both of traverse and inward feed so that a tapered cut results. It will be noted that there is no provision here for a graduated speed relation between the traverse and feed motors so that the taper would always be cut at a definite angle. However, if this angle should not be that of the pattern, there would result a slight over or under feed, depending on whether the pattern taper were more or less than that provided by the normal relative speed and this would result in periodic stopping or starting 30 of one or the other of these motors, thus cutting the taper in a series of slight steps comprising the taper at a constant angle determined by the fixed motor ratio and straight in or out feed or straight traverse motions, the general direction 35 of all being that of the taper of the pattern.

In Figures 31 to 34 a mechanical control of the traverse and feed is illustrated. Referring to these figures, the traverse of the carriage 2b is produced by rotation of a lead screw 300 while 40 the feed and retraction of the carriage 3b is produced by rotation in opposite directions of the feed screw 301. This feed screw is arranged to be driven in either of opposite directions through friction clutches shown at 302 and 303. Each 45 of these clutches has a member as 304 and 305, respectively, freely journaled on the feed shaft with either of which the feed screw may be coupled and these members 304 and 305 are each provided with a bevel gear as 306 and 307 which mesh with a common drive gear 308 so that they are driven continuously in opposite directions. This gear 308 is shown as driven through intermeshing spiral gears 309 and 310 from a continuously driven shaft 311. The lead screw 300 is 55 also continuously driven and has thereon a cylindrical nut 312 provided with a peripheral groove 313 within which may engage a friction shoe 314 pivoted at 315 to a portion 316 of the traversing carriage 2b. When this shoe 314 is out of engagement with the nut 312 it rotates freely with the lead screw 300 but by stopping its rotation as by pressing the shoe 314 thereagainst, it is held from rotation with the lead screw and is forced to traverse lengthwise thereof, moving the 60' traverse carriage 2b therewith. Also continuously rotated are three driving members 320, 321 and 322 which as shown are geared together so that the members 321 and 322 rotate in opposite directions and the member 323 rotates in the direction of the member 322. Within each of these members 320, 321 and 322, as shown best in Figures 33 and 34, are pivoted at 323 arcuate brake shoes such as 324 which may have frictional material on their outer faces, and these 70

shoes may be pressed apart as by rocking a cam element 325 positioned between their free ends so as to engage their respective rotary members to tend to be rotated thereby. The brake shoes 5 within the member 320 are mounted on a disk 326 to which is connected an arm 327 connected in turn by a link 328 to the shoe 314 so that when the brake members of the drive member 320 are expanded, the member 326 is rocked in a direction 10 to move the brake shoe 314 from the nut 312 thus to operatively disconnect the lead screw from the traverse carriage 2b so as to stop its traverse. The brake elements within the drive members 321 and 322 are carried by disks 330 and 331, 15 respectively, which are both connected through arms 332 and 333 with a rod 334 connected to the lever 335 which on rocking in either of opposite directions connects one or the other of the friction clutches 302 and 303 with the feed screw. 20 These parts are so adjusted that a small movement of the lever applies a differential force to the clutches 302 and 303, either one of which may preponderate to produce a resultant motion of the feed screw, while in mid-position of the 25 lever 335 both friction clutches are equally effective and the feed screw remains stationary. The cams 325 of the drive members 320, 321 and 322 are connected together as by the links 340, 341 and 342 with a lever 343 fulcrumed at 344 30 on the carriage 3b, the upper end of which is pivotally secured at 345 to the tracer carrier, as, for example, to the plate 40.

When the tracer is in its null position the parts are as shown in Figure 31. Neither of the driving elements 321 or 322 preponderates to move the rod 334, which is thus held in its central position, holding the frictional clutches 302 and 303 equally effective so that no motion of the feed screw results. There is thus no feed motion of 40 the tool 6 relative to the work W. At the same time the shoe 314 is in firm engagement with the nut 312 so that the traversing screw is effective to produce traverse of the tool relative to the work and the tracer relative to the pattern. 45 If now the tracer is moved outwardly as by reaching an outwardly inclined portion of the pattern, the lever 343 is rocked, tightening the brake elements against the drive member 322 and loosening the brake elements in the drive member 321. This causes rocking of the members 330 and 331 in a direction which loosens the grip on the drive member 322 and tightens it on the drive member 321 to equilibrium condition, pulling the bar 334 inwardly and producing 50 a greater frictional drag at the clutch 302 than at the clutch 303, thus starting the rotation of the feed shaft in a direction to retract the tool from the work and the tracer from the pattern. The speed of motion of the feed shaft is dependent on the amount of variation of the tracer from its null position as this determines the frictional over-balance of the driving element 322 from that of the element 321 and the extent of movement of the rod 334. At the same 55 time the friction elements within the drive member 326 are brought into driving engagement with this member so as to more or less withdraw frictional engagement tending to hold the nut 312 against rotation, which thus produces a less effective traverse connection so that the speed of traverse is slowed. The extent of this slowing is also dependent on the amount of motion of the tracer away from its null position, which is determined by the amount of the taper of the pattern. Thus the speeds of retraction and traverse 60

of the tool are adjusted in accordance with the taper of the pattern to operate on the work in accordance with the taper of the pattern.

If an abrupt shoulder is contacted by the tracer, the amount of its motion away from its null position is relatively large, as has been heretofore pointed out, and this results in a further motion of the rod 334 and a closer engagement of the friction clutch 302 and a relatively complete release of the clutch 303, thus increasing 5 the speed of retraction of the tool from the work and at the same time the shoe 314 is withdrawn completely from its braking engagement with the nut 312 so that the traverse motion completely stops. Thus a retracting motion of the tool without any traverse whatever is produced so that a sharp shoulder is formed on the work conforming to the sharp shoulder on the pattern. Should the tracer, on the other hand, meet with a receding taper on the work, 10 the lever 343 would be swung in the reverse direction, rendering the driving member 321 more effective than the member 322, thus moving the rod 334 in the opposite direction and causing the frictional engagement of the clutch 303 to be 15 greater than that of the clutch 302, thus to rotate the feed screw in a direction to feed the tool into the work and the tracer toward the pattern while the driving member 320 would also be rendered effective to somewhat reduce the braking friction against the nut 312 so as to decrease 20 the speed of traverse. Should the tracer fall off a sharp shoulder on the pattern, it would move immediately further from its null position in feeding direction which would further increase 25 the driving effect of the clutch 303 over that of the clutch 302, increasing the speed of inward feed of the tool and tracer and stopping the traverse by completely freeing the nut 312 to rotate with the lead screw 300. The actuating mechanism for the rod 334 and the shoe 314 thus constitutes an amplified power follow-up mechanism control.

In some cases it may be desirable for ease in building up any desired pattern to provide 45 a mechanism by which the pattern need not be continuous over those portions where a straight traversing feed of the tool is desired. This permits the use of separate blocks for building up the pattern as shown for example in Figure 35, 50 wherein the blocks 400, 401, 402, 403 and 404 are supported on a suitable table 405 on which they may be held as by forming this table as a magnetic table which may be energized from any convenient source of electric current to 55 hold the block thereto with great tenacity. It will be noted that these blocks define a configuration along their front edges which is discontinuous between the blocks 403 and 402 and elsewhere continuous, the forward faces of the 60 blocks 402 and 403 being in alignment and parallel with the direction of traverse. The block 404 is associated with the block 403 to provide a receding shoulder over the edge 406. The block 402 has a similar but shorter receding 65 shoulder at its edge 407. The block 401 presents a tapered face at 408 and the block 400 presents a straight forward face 409 parallel with the traverse direction. The tracer 21 is here so related to its controlling mechanism, whatever 70 this may be, that it is normally held in null relation as heretofore described, so that when its end is free the tracer will be in null position and the traversing mechanism only will be effective. It will thus remain in any position relative to feed 75

and retraction in which it may find itself at any time and thus define a straight cut along the work parallel to the direction of traverse. It will thus jump gaps in the discontinuous contour line of the pattern as between the blocks 402 and 403, which it could not do if it were biased by its supporting springs to other than the null position.

Means are provided with this mechanism, therefore, to produce a temporary bias away from null position wherever the pattern configuration is such that feed is required. This means, as shown, comprises an element 415 which follows along behind the tracer in its traversing movement and with which cooperate certain parts of the pattern. This element 415 as shown best in Figures 36 and 37 is formed as a vane, depending from pivotal supporting portions 416 at opposite ends from a supporting frame 417 carried by the tracer casing 30. As shown this frame 417 is substantially triangular in outline. Normally the vane 415 hangs perpendicular or nearly so, and preferably in contact with an adjustable stop screw 418 carried in a bracket arm 419 forming part of the frame 417. It is normally held yieldingly in such contact by means of a spring 420 secured at one end to the vane 415 and at the other end to a pin 421 extending from the bracket arm 419. This vane is also connected through a spring 422 to an arm 423 of a bell crank lever fulcrumed at 424 to a portion 425 of the frame 417. The other arm 426 of this bell crank lever is pivotally connected to the tracer at 427. The spring 422 acts in opposition to the supporting springs 36 and 46 of the tracer as heretofore described, in so far as their tendency to hold the tracer forwardly from its null position is concerned, but by relieving the tension on the spring 422 the mounting springs 36 and 41 are effective to bias the tracer toward the pattern, or in feed direction, away from its null relation. The spring 420, however, is sufficiently strong to hold the tracer in null position so long as the vane 415 remains vertical. Certain of the pattern blocks, however, or certain parts of these blocks, are made higher than others in position to engage the vane during the traverse and rock its lower end backwardly relative to the traverse direction, it being noted from Figure 36 that the vane 415 is positioned above the level of the tracer 21. Referring now to Figure 39, it will be seen that the block 402 is sufficiently high to engage the lower edge of the vane 415 and as the tracer passes along the forward face of this block and is about to pass over the shoulder portion 407, the vane has impinged on the block 402 and has been rocked to the position shown in Figure 40, so that the tracer is then biased by its supporting springs 60 to press against the pattern so that when it passes over the shoulder 407 it immediately moves forward in the feed direction out of null relation and causes the feed to be effective. This produces an inward travel of the feed carriage and the tool cuts the work with a shoulder corresponding to the shoulder 407 of the pattern. The block 401 is also a high block so that the tracer remains biased to a feed-in position away from null as long as it is in engagement with the receding edge contour 408. As the tracer passes against the face 409 of the block 400, it is held from inward feed and consequently it is no longer necessary to bias the tracer for inward motion from its null position, hence the block 400 may be a low block over which the vane 415 may pass without impingement

thereon so that it may drop to its normal position. Likewise the block 404 should be a high block to cause the tracer to feed inwardly over its shoulder 406, while the block 403 is a low block so that by the time the tracer reaches the discontinuous portion of its travel between the blocks 403 and 402, the vane 415 may have swung back into the position shown in Figure 35 so that the tracer will jump this gap by traversing motion only, the low block 403 permitting the vane to be returned to its normal vertical position before the tracer reaches the gap. Thus the tracer can follow pattern edge contours involving elevational changes following into the valleys and jumping discontinuous portions at constant elevations or depths. 15

While as shown the tool and tracer mechanism are mounted for movement, it will, of course, be evident that it might in some cases be found desirable to move the work rather than the tool in traverse or feed, or both, and that the pattern instead of the tracer mechanism might be movable either in traverse or feed, or both.

It should be understood that the foregoing description of certain embodiments of this invention has been given merely by way of example and that many other modifications and changes might be made without departing from the spirit or scope of this invention as defined by the appended claims.

I claim:

1. In combination, a tracer unit comprising a support, a tracer, resilient means for supporting said tracer from said support, and stops for limiting the lateral motion of said tracer relative to a rectilinear path in one direction, said resilient means being disposed to cause pressure exerted against said tracer throughout an angular range of at least 90° from said path to produce movement of said tracer having a component in one direction along said path, and a device responsive to position variations between said tracer and said support along said path. 30

2. In combination, a tracer unit comprising a support, a tracer, resilient means for supporting said tracer from said support, and stops for limiting the lateral motion of said tracer relative to a rectilinear path, said resilient means being disposed to cause pressure exerted against said tracer throughout an angular range of more than 90° from said path to produce movement of said tracer having a component in one direction along said path, and a device responsive to position variations between said tracer and said support along said path only. 45

3. A tracer unit comprising a support, a member carried by said support for movement relative thereto in a rectilinear direction, a tracer carried by said member for movement relative thereto in a rectilinear direction angularly disposed to said first-mentioned rectilinear direction, said unit including means tending to hold said member and tracer in definite relative positions, and a device responsive to position variations between said tracer and support. 55

4. A tracer unit comprising a support, a member carried by said support for movement relative thereto in a rectilinear direction, a tracer carried by said member for movement relative thereto in a rectilinear direction angularly disposed to said first-mentioned rectilinear direction, said unit including means for yieldingly holding said member and tracer out of their respective normal positions, and a device responsive to position variations between said tracer and said support. 60

5. A follow-up system including a unit com- 75

- prising a support, a member carried by said support for yielding movement in a rectilinear direction, a tracer carried by said member for yielding movement relative thereto in a rectilinear direction angularly disposed to said first-mentioned rectilinear direction, a controlling device responsive to position changes of said tracer relative to said support, and mechanism including said support responsive to said device.
6. In combination, a support, a member carried by said support for yielding movement in a rectilinear direction, a tracer carried by said member for rectilinear movement relative thereto in a direction angularly disposed to said first-mentioned movement, and a control device responsive only to movement of said tracer relative to said support in a rectilinear direction between said relatively angularly disposed directions.
7. A tracer unit comprising a support, a member carried by said support for movement relative thereto in a rectilinear direction, a tracer carried by said member for movement relative thereto in a rectilinear direction angularly disposed to said first-mentioned rectilinear direction, means for limiting the motions of said member and of said tracer relative to said member each in one direction from a normal position, said unit including means for yieldingly holding said member and tracer out of their respective normal positions, and a device responsive to position variations between said tracer and said support.
8. In combination, a unit comprising a support, a member carried by said support for movement relative thereto in a rectilinear direction, a tracer carried by said member for movement relative thereto in a rectilinear direction angularly disposed to said first-mentioned rectilinear direction, said unit including yielding means tending to hold said tracer in one position relative to said support, and means for moving said support controlled by the relative positions of said tracer and support and inactive only when said tracer is in a position relative to said support different from said one position.
9. In combination, a tracer unit comprising a support, a member carried by said support for movement relative thereto in a linear direction, a tracer carried by said member for movement relative thereto in a linear direction angularly disposed to said first-mentioned linear direction, said unit including means for yieldingly holding said member and tracer out of their respective normal positions, a controlling device responsive to position variations between said tracer and support, and means controlled by said device inoperative only when said tracer and said support are in their respective normal positions.
10. In combination, a tracer unit comprising a support, a member carried by said support for movement relative thereto in a linear direction, a tracer carried by said member for movement relative thereto in a linear direction angularly disposed to said first-mentioned linear direction, means for limiting the motions of said member and of said tracer relative to said member each in one direction from a normal position, said unit including means for yieldingly holding said member and tracer out of their respective normal positions, a controlling device responsive to position variations between said tracer and support, and means controlled by said device inoperative only when said tracer and said support are in their respective normal positions.
11. A tracer unit comprising a support, a member carried by said support for movement relative thereto in a linear direction, a tracer carried by said member for movement relative thereto in a linear direction angularly disposed to said first-mentioned linear direction, means for limiting the motions of said member and of said tracer relative to said member each in one direction from a normal position, said unit including means for yieldingly holding said member and tracer out of their respective normal positions, a controlling device responsive to position variations between said tracer and support, and means controlled by said device inoperative only when said tracer and said support are in their respective normal positions.
12. A tracer unit comprising a support, a member carried by said support for movement relative thereto in a linear direction, a tracer carried by said member for movement relative thereto in a linear direction angularly disposed to said first-mentioned linear direction, means for limiting the motions of said member and of said tracer relative to said member each in one direction from a normal position, said unit including means for yieldingly holding said member and tracer in their respective normal positions, a device responsive to position variations between said tracer and said support, and means acting under predetermined conditions to bias said yielding means to move said tracer and member out of their respective normal positions.
13. In combination, a tracer mechanism comprising a support, a member spring-supported from said support for movement relative thereto in a plane substantially parallel to said support and limited to one angular direction, a member spring-supported from said first-mentioned member for movement in a plane substantially parallel thereto and in a different angular direction from the motion of said first-mentioned member, and means responsive to the relative positions of said support and said second-mentioned member.
14. In combination, a tracer mechanism comprising a support, a member spring supported from said support for movement relative thereto in a plane substantially parallel to said support and limited to one angular direction, a member spring-supported from said first-mentioned member for movement in a plane substantially parallel thereto and in a different angular direction from the motion of said first-mentioned member, means for limiting the extent of movement of each of said members, and means responsive to the relative positions of said support and said second-mentioned member.
15. In combination, a tracer mechanism comprising a support, a set of leaf springs upstanding from said support in parallel relation, a plate carried by said springs spaced from said support and movable by flexing of said springs in one linear direction only, a set of leaf springs upstanding from said plate with their flexing directions angularly disposed to the line of motion of said plate relative to said support, a member carried by said second set of leaf springs, means for moving said member relative to said support, and means responsive to such movement from a predetermined relative position.
16. In combination, a tracer mechanism comprising a support, a post extending from said support, a pair of plates each having a hole through which said post loosely passes, means for supporting said plates from said support, the next adjacent plate with capability of motion transversely of said post in one linear direction only and the other plate from said adjacent plate with capability of motion relative to said adjacent plate in one direction only angularly related to

- said first-mentioned linear motion, said mechanism including means yieldingly holding said plates and support in predetermined positions, means for moving said other plate relative to 5 said support, elements carried by said other plate and said post, respectively, and means responsive to the relative positions of said elements.
17. A follow-up system including a unit comprising a support, a member carried by said support for yielding movement in a rectilinear direction, a tracer carried by said member for yielding movement relative thereto in a rectilinear direction angularly disposed to said first-mentioned rectilinear direction, means for limiting each of said movements in one direction, a controlling device responsive to position changes of said tracer relative to said support, and mechanism including said support responsive to said device.
18. In combination, a support, a member carried by said support for yielding movement in a rectilinear direction, a tracer carried by said member for rectilinear movement relative thereto in a direction angularly disposed to said first-mentioned movement, means for limiting said movements each in one direction, and a control device responsive only to movement of said tracer relative to said support in a direction between said relatively angularly disposed directions.
19. In combination, a tracer unit comprising a support, a tracer, means for mounting said tracer from said support with capacity for movement in any direction in one plane, and a device responsive to a single component only of such motion in a rectilinear path.
20. In combination, a tracer unit comprising a support, a tracer, means for mounting said tracer on said support with capacity for movement in any direction in a plane, a pattern support, a work holder, a tool, means for traversing said tracer support relative to said pattern and said tool relative to said work holder, means for producing relative motions of said tracer toward and from said pattern and of said tool toward and from work carried by said work holder, and means responsive to one rectilinear component only of the motion of said tracer relative to its support for controlling said toward and from moving means and said traversing means.
21. In combination, a tracer unit comprising a support, a tracer, means for mounting said tracer on said support with capacity for movement in any direction in a plane, a pattern support, a work holder, a tool, means for traversing said tracer support relative to said pattern and said tool relative to said work holder, means for producing relative motions of said tracer toward and from said pattern and of said tool toward and from work carried by said work holder, means responsive to one rectilinear component only of the motion of said tracer relative to its support for controlling said toward and from moving means, and means controlled by motion of said toward and from moving means controlling said traversing means.
22. In combination, a support, a member carried by said support for yielding movement in a linear direction, a tracer carried by said member for movement relative thereto in a direction angularly disposed to said first-mentioned movement, means for limiting said movements each in one direction, and a control device responsive only to movement of said tracer relative to said support in a direction between said relatively angularly disposed directions, said device comprising a pair of relatively movable condenser plates one carried by said support and the other movable with said tracer.
23. In combination, a support, a member carried by said support for yielding movement in a linear direction, a tracer carried by said member for movement relative thereto in a direction angularly disposed to said first-mentioned movement, and a control device responsive only to movement of said tracer relative to said support in a direction between said relatively angularly disposed directions, said device comprising a valve having ports controlled by such between movement, and fluid pressure operated mechanism controlled by said valve.
24. In combination, a support, a member carried by said support for yielding movement in a linear direction, a tracer carried by said member for movement relative thereto in a direction angularly disposed to said first-mentioned movement, means for limiting said movements each in one direction, and a control device responsive only to movement of said tracer relative to said support in a direction between said relatively angularly disposed directions, said device comprising a valve having ports controlled by such between movement, and fluid pressure operated mechanism controlled by said valve.
25. In combination, a support, a member carried by said support for yielding movement in a linear direction, a tracer carried by said member for movement relative thereto in a direction angularly disposed to said first-mentioned movement, an electrically controlled device responsive only to movement of said tracer relative to said support in a direction between said relatively angularly disposed directions, and electrically actuated mechanism controlled by said device.
26. In combination, a support, a member carried by said support for yielding movement in a linear direction, a tracer carried by said member for movement relative thereto in a direction angularly disposed to said first-mentioned movement, means for limiting said movements each in one direction, an electrically controlled device responsive only to movement of said tracer relative to said support in a direction between said relatively angularly disposed directions, and electrically actuated mechanism controlled by said device.
27. In combination, a tool, a work holder, a pattern, a tracer support, means for producing relative traverse and relative feed and retracting movements between said tool and work holder and between said tracer support and pattern, a member carried by said support and yieldingly movable relative thereto at an angle to said feed and retracting movements, a tracer carried by said member for yielding movement at an angle to said member movement, said feed and retracting movements lying between said member movement and the tracer movement relative to said member, and means responsive to the component of movement of said tracer relative to said support in line with said feed and retracting movements for controlling the traversing and feeding and retracting means.
28. In combination, a tool, a work holder, a pattern, a tracer support, means for producing relative traverse and relative feed and retracting movements between said tool and work holder and between said tracer support and pattern, a member carried by said support and yieldingly movable relative thereto at an angle to said feed and retracting movements, a tracer carried by said

member for yielding movement at an angle to said member movement, said feed and retracting movements lying between said member movement and the tracer movement relative to said member, means to limit the movements of said tracer and member toward said pattern, and means responsive to the component of movement of said tracer relative to said support in line with said feed and retracting movements for controlling the traversing and feeding and retracting means.

29. In combination, a tool, a work holder, a pattern, a tracer support, means for producing relative traverse and relative feed and retracting movements between said tool and work holder and between said tracer support and pattern, a member carried by said support and yieldingly movable relative thereto at an angle to said feed and retracting movements, a tracer carried by said member for yielding movement at an angle to said member movement, said feed and retracting movements lying between said member movement and the tracer movement relative to said member, and means responsive to the component of movement of said tracer relative to said support in line with said feed and retracting movements for controlling the rate of said traversing movement and the direction and rate of said feeding or retracting movements to cause said tool to operate on the work in accordance with said pattern.

30. In combination, a tool, a work holder, a pattern, a tracer support, means for producing relative traverse and relative feed and retracting movements between said tool and work holder and between said tracer support and pattern, a member carried by said support and yieldingly movable relative thereto at an angle to said feed and retracting movements, a tracer carried by said member for yielding movement at an angle to said member movement, said feed and retracting movements lying between said member movement and the tracer movement relative to said member, means to limit the movements of said tracer and member toward said pattern, and means responsive to the component of movement of said tracer relative to said support in line with said feed and retracting movements for controlling the rate of said traversing movement and the direction and rate of said feeding or retracting movements to cause said tool to operate on the work in accordance with said pattern.

31. In combination, a tool, a work holder, a pattern, a tracer support, a motor for traversing said tool relative to the work and said tracer support relative to said pattern, a feed motor for imparting relative feed and retracting motions between said tool and work holder and between said tracer support and pattern, a member yieldingly carried by said support for linear movement at an angle to the feed and retracting direction, a tracer yieldingly carried by said member to move in a linear direction at an angle to the feed direction, said feed direction lying between said member movement and said tracer movement relative to said member, and control means for said motors responsive to components of said tracer movement in the direction of said feed and retraction.

32. In combination, a tool, a work holder, a pattern, a tracer support, a motor for traversing said tool relative to the work and said tracer support relative to said pattern, a feed motor for imparting relative feed and retracting motions between said tool and work holder and between said tracer support and pattern, a member yieldingly carried by said support for linear movement at an angle

to the feed and retracting direction, a tracer yieldingly carried by said member to move in a linear direction at an angle to the feed direction, said feed direction lying between said member movement and said tracer movement relative to said member, stops for limiting the motion of said member and the pattern-controlled motion of said tracer relatively to said member in directions inclined toward said pattern, and control means for said motors responsive to components of said tracer movement in the direction of said feed and retraction.

33. In combination, a tool, a work holder, a pattern, a tracer support, a fluid pressure motor for traversing said tool relative to the work and said tracer support relative to said pattern, a fluid pressure feed motor for imparting relative feed and retracting motions between said tool and work holder and between said tracer support and pattern, a member yieldingly carried by said support for linear movement at an angle to the feed and retracting direction, a tracer yieldingly carried by said member to move in a linear direction at an angle to the feed direction, said feed direction lying between said member movement and said tracer movement relative to said member, a source of fluid under pressure, a fluid pressure valve having ports communicating with said motors and said source, and means responsive to components of tracer movements in the direction of feed and retraction for controlling the opening and closing of said ports.

34. In combination, a tool, a work holder, a pattern, a tracer support, a fluid pressure motor for traversing said tool relative to the work and said tracer support relative to said pattern, a fluid pressure feed motor for imparting relative feed and retracting motions between said tool and work holder and between said tracer support and pattern, a member yieldingly carried by said support for linear movement at an angle to the feed and retracting direction, a tracer yieldingly carried by said member to move in a linear direction at an angle to the feed direction, said feed direction lying between said member movement and said tracer movement relative to said member, stops for limiting the motion of said member and the pattern-controlled motion of said tracer relative to said member in directions inclined toward said pattern, a source of fluid under pressure, a fluid pressure valve having ports communicating with said motors and said source, and means responsive to components of tracer movements in the direction of feed and retraction for controlling the opening and closing of said ports.

35. In combination, a tool, a work holder, a pattern, a tracer mechanism, fluid pressure means for effecting relative traversing motions between said tool and holder and between said tracer and pattern, fluid pressure means for effecting relative feed and retractive motions between said tool and holder and between said tracer and pattern, and valve means controlled by small pattern-produced departure of a portion of said tracer mechanism in line with the feed and retractive motions from a normal relation to control said motors in corrective directions to cause said tool to operate on the work in accordance with the contour of said pattern.

36. In combination, a tool, a work holder, a pattern, a tracer mechanism, a rotary lead shaft for effecting relative traverse between said tool and work and between said tracer mechanism and pattern, a rotary feed shaft for imparting rela-

5 tive feed and retractive motions between said tool and work holder and between said tracer mechanism and pattern, said tracer mechanism having a pair of relatively movable portions, the 10 position of one of which is controlled by the contour of said pattern, and means controlled by small relative departures of said tracer portions from a null relative position for controlling the 15 traverse motion produced by said lead shaft and the feed and retracting motions produced by said feed shaft in relation to tend to minimize such variations.

15 37. In combination, a tool, a work holder, a pattern, a tracer mechanism, a rotary lead shaft for effecting relative traverse between said tool and work and between said tracer mechanism and pattern, a rotary feed shaft for imparting relative feed and retractive motions between said tool and work holder and between said tracer mechanism and pattern, said tracer mechanism having a pair of relatively movable portions, the 20 position of one of which is controlled by the contour of said pattern, a friction device for operatively coupling said lead shaft to effect said traversing motion, a pair of oppositely rotating drive means, friction devices for operatively connecting either of said drive means to said feed shaft to drive said feed shaft in either of said opposite directions to effect feed or retracting 25 motions, and means controlled by relative departures from a null relative position of said tracer portions for controlling said friction devices to minimize such departures.

30 38. In combination, cooperating pairs of parts comprising a tool and work holder, and a pattern and tracer mechanism, respectively, a traversing carriage, a feed carriage on said traversing carriage and carrying one of each of said pairs of parts, a lead screw for traversing said traversing carriage, a feed screw for producing feed and retracting movements of said feed carriage, a pair of drive members rotatable in opposite directions, friction clutches for selectively connecting either of said drive members to said feed screw, 35 a nut on said lead screw, means for frictionally coupling said nut non-rotatably to said feed carriage, said tracer mechanism having a pair of relatively movable portions, the position of one being controlled by the contour of said pattern, and means controlled by relative departures of 40 said portions from a relatively null relation to actuate said clutches and coupling means in relations to minimize said departures.

35 39. In combination, cooperating pairs of parts comprising a tool and work holder, and a pattern and tracer mechanism, respectively, a traversing carriage, a feed carriage on said traversing carriage and carrying one of each of said pairs of parts, a lead screw for traversing said traversing carriage, a feed screw for producing feed and retracting movements of said feed carriage, a pair of drive members rotatable in opposite directions, friction clutches for selectively connecting either of said drive members to said feed screw, a nut on 45 said lead screw, means for frictionally coupling said nut non-rotatably to said feed carriage, said tracer mechanism having a pair of relatively movable portions, the position of one being controlled by the contour of said pattern, three rotary control members, two of which rotate in reverse directions, rocking elements frictionally engageable with said control members, an actuating element for said friction clutch members connected to the rocking elements of said two members to actuate one or the other of said friction

5 clutches in accordance with which of said elements has the dominating frictional engagement with its control member, an actuating element for said coupling means connected to the third of said elements to stop the rotation of said nut when said third element is frictionally engaged by its control member, and means actuated by relative departures of said tracer mechanism portions from a relative null relation to unbalance the frictional drag of said two control members and their respective elements to actuate said feed screw in one or the other direction and to increase the friction between said third control member and its element to release the frictional drag on said nut to thereby slow the traverse of said 15 traverse carriage all in relations to minimize such departures.

20 40. In combination, a discontinuous pattern presenting guiding edge contours where a change in elevation occurs, and a tracer for traversing said pattern, said tracer and pattern having cooperating portions for causing said tracer to follow said change in elevation contours and elsewhere inoperative, and means tending to retain said tracer continuously at a constant elevation when 25 said cooperating portions become inoperative during a traverse.

25 41. In combination, a pattern, a tracer, means for producing relative traversing movements between said pattern and tracer, means for producing relative feed and retraction between said pattern and tracer transverse to the direction of traverse, said pattern presenting an edge contour to said tracer discontinuous in those portions parallel to the traverse direction and elsewhere continuous, and cooperating means on said pattern and tracer for causing said feeding and retraction-producing means to be actuated in relation to said traversing movement to cause said tracer to follow said pattern contour on said continuous 30 portions and parallel to the line of traverse as determined by the previous continuous contour portion where its contour is discontinuous.

35 42. In combination, a pattern, a tracer mechanism, means for producing relative traversing motions between said pattern and mechanism, means for producing relative feed and retractive motions transverse to the direction of traverse, said pattern presenting an edge contour to said tracer mechanism discontinuous in those portions parallel to the traverse direction and elsewhere continuous, said tracer mechanism having a portion for following said contour normally biased to a null position in said mechanism ineffective to actuate said feed and retraction-producing means, 40 whereby said tracer portion follows said discontinuous contour portions by traverse only, and cooperating elements on said pattern and tracer mechanism for biasing said tracer portion in feed direction from said null position as said contour 45 approaches a valley, whereby said portion follows said contour into said valley, and means actuated by departures of said portion from null position in said mechanism to actuate said feed and retraction-producing means in corrective direction.

45 43. In combination, a pattern, a tracer mechanism, means for producing relative traversing motions between said pattern and mechanism, means for producing relative feed and retractive 50 motions transverse to the direction of traverse, said pattern presenting an edge contour to said tracer mechanism discontinuous in those portions parallel to the traverse direction and elsewhere continuous, said tracer mechanism having 55

5 a portion for following said contour normally biased to a null position in said mechanism ineffective to actuate said feed and retraction-producing means, whereby said tracer portion follows said discontinuous contour portions by traverse only, and cooperating elements on said pattern and tracer mechanism for biasing said tracer portion in feed direction from said null position as said contour approaches a valley, 10 whereby said portion follows said contour into said valley, and means actuated by departures of said portion from null position in said mechanism to actuate said feed and retraction-producing means in corrective direction, and said 15 traverse-producing means relatively thereto.

44. In combination, a pattern, a tracer mechanism, means for producing relative traverse and relative feed and retractive motions perpendicular to said traverse between said pattern and 20 tracer, said mechanism having a relatively movable pattern-engaging portion, said pattern having an edge contour traced by said portion discontinuous in parts parallel with the line of traverse and elsewhere continuous, a member 25 traversible with and back of said tracer portion, an element pivoted to said member, operative yielding connections between said element and portion for normally holding said element and portion in a null position, said pattern having

projecting parts with which said element is engaged to be moved by relative traverse therebetween to apply yielding pressure to said portion in feed direction away from said null position, said parts being located with reference to said pattern to cause said portion to tend to follow receding parts of said contour, and means controlled by movement of said portion away from null position to actuate said motion-producing means in corrective relations. 5

45. In combination, a pattern, a tracer mechanism having a point for engagement with an edge of said pattern, a tool, a work support, means for producing motions of relative traverse and relative feed and retraction between said 15 pattern and mechanism and between said tool and work support, said tracer point being mounted for motion in the line of feed and in the direction of traverse relative to said tool, and means responsive to such motion in the line of feed from 20 a normal relative position to actuate said motion-producing means in corrective relation, said tracer point having a pattern-engaging contour similar to the active portion of said tool and of a width greater than that of said tool by sub- 25 stantially the amount of the relative motion between said point and said tool in the direction of traverse. 10

WILFRED H. HOWE.
